UNITED STATES PATENT OFFICE.

AUGUST JOHNSON, OF NORTH MANKATO, MINNESOTA.

INSULATOR-PROTECTOR.

1,177,867.

Specification of Letters Patent. Patented Apr. 4, 1916.

Application filed November 2, 1914. Serial No. 869,960.

To all whom it may concern:

Be it known that I, AUGUST JOHNSON, a citizen of the United States, residing at North Mankato, in the county of Nicollet 5 and State of Minnesota, have invented a new and useful Insulator-Protector, of which the following is a specification.

The present invention relates to improvements in insulator protectors, one object of 10 the invention, being the provision of an incasing member adapted to surround the usual porcelain or glass insulators now in use upon telephone and telegraph poles and to thus protect the same against breakage by 15 thrown stones or objects, the same including a two membered casing adapted to surround the insulator and be held thereaway from by insulating material so as to reduce the liability of the short circuiting of the support- 20 ed wire.

A further object of the present invention, is the provision of a novel construction of insulator protector, which is simple, inexpensive and durable in construction, and which 25 is thoroughly efficient and practical in use.

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed without 35 departing from the spirit of the invention.

In the drawings—Figure 1 is a side elevation of the present protector taken from the locked side thereof, dotted lines illustrating the position of the insulator therewithin. 40 Fig. 2 is a side elevation of the same. Fig. 3 is a top plan view of the same. Fig. 4 is a view in elevation showing the two sections of the protector open. Fig. 5 is a top plan view thereof.

45 Referring to the drawings, the numeral 1 designates the insulator which is of the usual construction. The protector consists of the two sections 2 preferably made of metal and hinged together as at 3 with a 50 permanent hinge upon one edge thereof, the opposite edge being provided with the respective sleeves 4 and 5 for the reception of the locking pin 6 which is insertible there-

through similar to the usual door hinges now in use. 55

Each section of the present device is slotted from the edge adjacent to the hinge of the members 4 and 5 transversely as at 7 to a point centrally of the member where it terminates in the enlargement 8 which is 60 surrounded by the insulation 9 so that the line wire 10 will not be affected. It will be noted that the slot 7 is at a point above the upper end of the pin 6 when the parts are assembled. 65

In order to support the protector away from the insulator 1 so that a dome member will surround the same and be out of contact therewith, a plurality of buttons 11 made of an insulating material, preferably cork, 70 are attached to and carried upon the inner face of the sections 2 of the insulator protector and are so disposed as to engage the sides of the insulator 1 below the line wire 10, or as particularly illustrated in Figs. 75 1 and 2.

From the foregoing description, it is evident that the present insulator protector may be readily disposed upon the insulator 1 with the line wire 10 in position, it being 80 simply necessary to slip the same upon the opposite side or from right to left as shown in Fig. 2, with the sections spread open as shown in Fig. 5, so that the slots 7 in the free portions of the sections will permit the line 85 wire 10 at each side of the insulator to pass therein so that the insulated portion 9 thereof will surround the wire, with the insulated buttons 11 disposed upon the body of the insulator thereabout. When this is accomplished, the members 4 and 5 aline so that 90 the locking pin 6 may be inserted from above therethrough to thus lock the protector in position upon the insulator. With the protector thus assembled upon the insulator, 95 such protector being made of metal, it is evident that stones or other objects thrown thereat, will in no way damage or break the glass or porcelain insulator 1, the cork buttons 11 relieving any jar from the protector 100 thereagainst and at the same time acting as an insulator to prevent any short circuiting of the current from the line wire 10.

What is claimed is:

An insulator protector composed of two 105 sections hinged together and adapted when

swung together to inclose an insulator, the free portions of said sections having transverse slots extending toward the hinge for receiving a wire supported by the insulator
5 when the sections are swung together to inclose the insulator, and means for attaching the free portions of said sections together.

Copies of this patent may be obtained for five cents each, by addressing the "Commissioner of Patents,
Washington, D. C."

In testimony that I claim the foregoing as my own, I have hereto affixed my signature in the presence of two witnesses.

AUGUST JOHNSON.
